COMBINED PLAYGROUND CLIMBER AND SLIDE

Robert S. Wormser, Hillsdale, Mich., assignor to Game-Time, Inc., Litchfield, Mich., a corporation of Michigan

Filed Mar. 4, 1968, Ser. No. 10,816

Term of patent 14 years

U.S. Cl. D34—5
Int. Cl. D21—03

FIG. 1

FIG. 2

FIG. 4

FIG. 1 is a front and side elevational perspective view of a combined playground climber and slide in accord with my new design,

FIG. 2 is a top plan view of the climber and slide of the invention,

FIG. 3 is a front elevational view, and

FIG. 4 is a rear elevational view of the design of the invention.

I claim:

An ornamental design for a combined playground climber and slide, substantially as shown and described.
